LINE TIGHTENING BASEMENT CLOTHES-
LINE BRACKET

Frank Schudy, Mission Hills, Kans.

Application November 7, 1947, Serial No. 784,681

14 Claims. (Cl. 211—119.15)

1

My invention relates to line tightening clothesline brackets, and more particularly to an adjustable line tightening clothesline bracket for use in basements and similar places. This is a continuation in part of my application Serial No. 754,494, filed June 13, 1947, on Line tightening adjustable clothesline bracket.

It is the principal purpose of my invention to provide a bracket that is suitable for supporting clotheslines in a basement. In the use of my invention the brackets are secured to the ceiling beams or floor joists at the ceiling of the basement and are adapted to be mounted on such beams or joists that extend either in the direction in which the lines are to extend or crosswise thereof.

It is more particularly a purpose of my invention to provide brackets of the above mentioned character that are easily installed and which require no maintenance after installation and which are adjustable in length in order to locate the clothesline at a desirable height even though the basements in which the same are to be used are of various heights.

It is a further purpose of my invention to provide a bracket of the above mentioned character, which is so mounted on a floor joist or joists that the same can be swung out of normal operative position so that the bracket and clotheslines will be out of the way close to the joists. In order to accomplish this, each of said brackets is mounted on a single bolt or other headed fastening element that secures the same to a joist and is provided with detachable bracing means, which may be detached from the bracket and the bracket swung and secured by any suitable means in a position adjacent the joists.

It is another purpose of my invention to provide a clothesline bracket of the above character, by means of which a plurality of clotheslines are supported in parallelism, preferably, five lines being provided, that are mounted on a cross bar so as to properly space the lines in such a manner that articles hung from the various lines will dry readily, the spacing permitting air to pass between the articles that are hung on the lines to accomplish such drying.

It is still a further purpose of my invention to provide means for adjusting the position of the transverse bar-like member upon which the plurality of clotheslines are mounted to tighten up the lines, said means comprising self-locking tightening means that are crank operated, and which embody screw-threaded means providing the self-locking adjusting means.

Other objects and advantages of my invention will appear as the description of the drawings proceeds. I desire to have it understood, however, that I do not intend to limit myself to the particular details shown or described, except as defined by the claims.

In the drawings:

Fig. 1 is a view in side elevation of one of my improved clothesline brackets, showing the same applied to a joist extending transversely of the direction of length of the lines, with bracing means connected with a transverse joist adjacent the joist on which the bracket is mounted, said joists and said bracing means being partly broken away.

Fig. 2 is a view similar to Fig. 1, showing one of my improved clothesline brackets applied to a joist that runs parallel to the length of the clothesline.

Fig. 3 is a fragmentary sectional view taken on the line 3—3 of Fig. 1.

Fig. 4 is a section taken on the line 4—4 of Fig. 2.

Fig. 5 is a section taken on the line 5—5 of Fig. 1, and

Fig. 6 is a view in elevation of the line carrying cross bar.

Referring in detail to the drawings, my improved clothesline bracket is shown in Fig. 1 as being applied to a joist 10 and comprises a bracket comprising an upper angle member 11 and a lower angle member 12, which lower angle member 12 has substantially an L-shape having a vertically extending attaching portion 60 and a transversely extending foot portion 13 at the lower end thereof. The upper angle member 11 has a plurality of uniformly spaced openings 14 in the one leg 15 thereof and a plurality of similarly uniformly spaced openings 16 in the other leg 11 thereof. A bolt or other similar screw-threaded headed member 18 extends through the uppermost opening 16 in the position of the device shown in Fig. 1, said bolt being provided with a washer 19 and a nut 20, as shown in Fig. 1 of the drawings, so that the angle member 11 can be swung about the bolt 18 as an axis into a position adjacent the joist 10 when this is desired.

The angle member 12 is secured to the angle member 11 by means of a pair of bolts 21, which extend through a pair of the openings 16 and a pair of aligned openings 22 in the one leg 23 of attaching portion 60 of the angle member 12, said angle member 12 having a row of said openings 22 uniformly spaced along said leg 23. Uniformly spaced openings 24 are also provided in

the leg 25 of attaching portion 60 of the angle member 12. The openings 22 are spaced the same distance apart as the openings 16 and thus the bracket members 11 and 12 can be adjustably secured together in a large number of different relative positions to obtain any desired adjustment of the bracket member for location of the horizontal foot portion 13 thereof at desired spacing below the joint 10. By providing similar uniformly spaced openings 14 and 24 in the legs 15 and 25 the members 11 and 12 can also be secured together in said relatively adjustable positions, but with the legs 25 and 15 in engagement instead of the legs 23 and 17, should this be desired. However, by securing the members 11 and 12 together by securing of the flanges or legs 17 and 23 as shown in Fig. 1, the resulting bracket can be secured to the joist 10 as shown in Fig. 1, or to the side of a joist 10', as shown in Fig. 2. However, when the bracket is secured to the side of the joist 10', then the bolt 18 is passed through one of the openings 14 in the leg 15, as will be obvious from Fig. 2.

A bracing member 26 is provided, which may be bent so as to provide an end portion 27 at the lower end thereof, through which a bolt 28 is passed, said bolt being also passed through one of the openings 22 in the leg 23 of the member 12 to secure the lower end of the brace 26 to the bracket member. Said brace is further provided with a bent end 29 at the upper end thereof, which is engaged with the joist 30 next to the joist 10 and secured thereto by means of a bolt 31, said bolt being provided with a washer 32 and a nut 33. In order to swing the bracket about the axis of the bolt 18, it is necessary to detach the brace 26 from the bracket by removal of the bolt 28 when it is desired to swing the bracket to an out-of-the-way position adjacent the joist 10, said bolt being, preferably, provided with a wing nut to facilitate removal. It will be noted that the brace 26 is secured to the joist 30 on the side thereof remote from that on which the bracket is secured to the joist 10.

When the bracket is arranged in the position shown in Fig. 2 the brace 26' is not bent but is left flat, and a bolt 28' is used for securing the lower end of the bracket 26' to the leg 25 of the lower bracket member 12, being passed through one of the openings 24, preferably, the lowermost one, for securing the bracing member to the bracket. Also the upper end of the brace 26' is left straight and a bolt 31' is passed through one of a plurality of openings 34 in the upper end of said brace and through an opening in the joist 10' spaced a substantial distance from the opening through which the bolt 18 is passed. In order to swing the bracket into an out-of-the-way position when arranged on a joist as shown in Fig. 2, the bolt 28' can be removed to permit such swinging about the axis of the bolt 18. While bolts are shown in the drawings for securing the braces and the brackets to the joists, screws or other suitable screw-threaded headed fastening elements can be used, although bolts are preferred.

The laterally extending foot portion 13 of the lower bracket member 12 is, preferably, made integral with the upstanding portion 60 of said bracket and has an upstanding flange or leg 35 and a horizontal flange or leg 36, the flange or leg 35 being welded to the flange or leg 25 and the flange or leg 36 being continuous with the flange or leg 23 of the upstanding portion of the

bracket 12. The bottom flange or horizontal leg 36 is provided with a slot 37 therein extending longitudinally thereof. A slideable block 38 which has a substantially circular body portion has a downwardly extending reduced portion 39, which is also circular and which is mounted in the slot 37, thus providing for sliding movement of the block 38 in the slot longitudinally of the foot portion 13 in the slot 37.

10 A screw-threaded opening 40 is provided in the block 38 that extends transversely thereof and a screw-threaded opening 41, that intersects the opening 40, extends axially of the member 38 and of the reduced portion 39, opening out through the bottom face of said reduced portion 39. A screw-threaded headed member 42 engages in the screw-threaded opening 41 and extends loosely through an opening 43 in a channel member 44, which has flanges 45 that lie on opposite sides of the foot 13, and also extends through an opening 46 in an angle member 47, which angle member extends transversely of the channel member 44 and is fixed thereto, as by means of rivets 48. Thus the angle member 47 is guided for movement lengthwise of the foot portion 13 by means of the slot 37 cooperating with the reduced portion 39 and also by means of the flanges 45 of the channel member, which lie closely adjacent the upstanding leg 35 of the foot portion 13 and the horizontal leg 36 thereof.

20 The angle member 47 constitutes a line carrying member having a vertical leg portion 49, which is provided with a plurality of uniformly spaced openings 50 therein, the number being variable, but five being shown in the particular embodiment illustrated in the drawings. Thus five parallel lines can be hung from the line carrying member 47 and a similar line carrying member that is provided on a similar bracket at a predetermined spaced distance from the one illustrated, as will be obvious. The lines that are mounted on the line carrying angle member 47 may be of any desired material or character, a line 51 being shown, which is provided with a knot 52 at the end thereof for securing the same to the line carrying member 47.

30 A screw-threaded shaft 53 is engaged in the screw-threaded opening 40 of the block 38, said shaft having a collar 54 welded thereto, which engages the outer face of the leg 24 of the lower bracket member 12 and having a crank portion 55 thereon that is provided with a crank handle 56, by means of which the shaft can be rotated. It will be obvious that rotation of the crank 55 in the proper direction will cause the block 38 to be drawn toward the end of the foot portion 13 that joins the upstanding part of the lower bracket member 12, whereby the lines 51 can be tensioned as may be desired. Due to the provision of the foot portion and the relatively long slot for guided movement of the block 38, a very substantial adjustment in the position of the line carrying member 47 can be obtained, and inasmuch as there is a relatively fine screw-thread provided in the opening 40 and on the screw-threaded portion of the shaft 53, the adjusting means will be self locking so as to hold the lines 51 under tension to any desired extent.

40 In placing the brackets in position on the joists, said brackets are spaced such a distance apart that with the blocks 38 on the brackets near the extremity of the foot portion 13 remote from the upstanding portion 60 of the lower bracket member 12, the lines 51 will not be tightened fully. Rotation of the crank 55 in the

above referred to manner on either or both of the brackets will cause the blocks 38 to move toward the crank ends of the shafts 53 to tighten the lines 51. In practice, the adjustment possible at each bracket is about four inches, which makes it possible to tighten the lines from either end, and if desired, the lines can be tightened at one end only if this is found to be all that is necessary. However, if the lines tend to stretch as weight thereon is increased, tightening can be accomplished by further turning the crank that has been previously used for adjusting the tension on the lines, or the other crank at the other end of the lines can be turned to further tighten the same. Thus the lines can be mounted at a predetermined desired spaced distance from the ceiling of the basement without the use of any other supports than the brackets. The lines that are used are of such a character that articles can be secured thereto in the usual manner by the usual clothes pins.

A strong structure is provided, which is adequate for supporting the plurality of lines 51 loaded with damp clothing or other articles to be dried, and the brackets I have provided are of such a character that a large amount of washing can be dried in a relatively limited space, such as exists in a basement, and said lines can be located at a convenient height from the basement floor, which is usually about six feet, and at the same time my improved basement clothesline brackets are of such a character that the same can be moved out of a depending position from the joists so that the same will not be in the way when the lines are not in use, and at the same time the clotheslines will also be swung to a position such that these will not be in the way.

What I claim is:

1. A clothesline bracket comprising an upper bracket member, means for pivotally mounting said upper bracket member on a support, a lower bracket member having an elongated body portion longitudinally adjustably mounted on said upper bracket member and having a foot portion integral with and extending perpendicularly to said elongated body portion, a line carrying member extending transversely of said foot portion, and means for adjusting the position of said line carrying member longitudinally of said foot portion comprising a member mounted for longitudinal sliding movement on said foot portion.

2. A clothesline bracket comprising an upper bracket member angular in cross section, means for pivotally mounting said upper bracket member on a support, a lower bracket member having an elongated body portion angular in cross section longitudinally adjustably mounted on said upper bracket member and having a foot portion integral with and extending perpendicularly to said elongated body portion, a line carrying member extending transversely of said foot portion and means for adjusting the position of said line carrying member longitudinally of said foot portion comprising a member mounted for longitudinal sliding movement on said foot portion having said line carrying member fixedly mounted thereon.

3. A clothesline bracket comprising an upper bracket member, means for pivotally mounting said upper bracket member on a support, a lower bracket member having an elongated body portion longitudinally adjustably mounted on said upper bracket member and having a foot portion extending laterally from said elongated

body portion, a bracing member connected with said lower bracket member adjacent said foot portion, a line carrying member extending transversely of said foot portion, and means for adjusting the position of said line carrying member longitudinally of said foot portion.

4. A clothesline bracket comprising an upper bracket member, means for mounting said upper bracket member on a support, a lower bracket member having an elongated body portion longitudinally adjustably mounted on said upper bracket member and having a foot portion extending laterally from said elongated body portion, a block longitudinally slidably mounted on said foot portion, a line carrying member mounted on said block and extending transversely of said foot portion, and means for adjusting the position of said block longitudinally of said foot portion.

5. A clothesline bracket comprising an upper bracket member, means for mounting said upper bracket member on a support, a lower bracket member having an elongated body portion longitudinally adjustably mounted on said upper bracket member and having a foot portion extending laterally from said elongated body portion, a block longitudinally slidably mounted on said foot portion, a channel member carried by said block with the flanges thereof in embracing relation to said foot portion, a line carrying member mounted on said channel member and extending transversely of said foot portion, and means for adjusting the position of said block longitudinally of said foot portion.

6. A clothesline bracket comprising an upper bracket member, means for mounting said upper bracket member on a support, a lower bracket member having an elongated body portion longitudinally adjustably mounted on said upper bracket member and having a foot portion extending laterally from said elongated body portion, said foot portion having a longitudinally extending slot therein, a block mounted on said foot portion and having a reduced portion extending into said slot, a line carrying member depending below said foot portion, extending transversely thereof and secured to said reduced portion, and means for adjusting said block longitudinally of said slot.

7. A clothesline bracket comprising an upper bracket member, means for mounting said upper bracket member on a support, a lower bracket member having an elongated body portion longitudinally adjustably mounted on said upper bracket member and having a foot portion extending laterally from said elongated body portion, said foot portion having a longitudinally extending slot therein, a block mounted on said foot portion and having a reduced portion extending into said slot, a line carrying member depending below said foot portion extending transversely thereof and secured to said reduced portion and self locking means for adjusting said block longitudinally of said slot.

8. A clothesline bracket comprising an upper bracket member, means for mounting said upper bracket member on a support, a lower bracket member having an elongated body portion longitudinally adjustably mounted on said upper bracket member and having a foot portion extending laterally from said elongated body portion, said foot portion having a longitudinally extending slot therein, a block mounted on said foot portion and having a reduced portion extending into said slot, a line carrying member

depending below said foot portion, and extending transversely thereof, a channel member fixed to said line carrying member, means for securing said line carrying member to the reduced portion of said block with the flanges of said channel member in embracing relation to said foot portion, and means for adjusting said block longitudinally of said slot.

9. A clothesline bracket comprising an upper bracket member angular in cross section, means for pivotally mounting said upper bracket member on a support, a lower bracket member having an elongated body portion angular in cross section longitudinally adjustably mounted on said upper bracket member and having a foot portion angular in cross section extending laterally from said elongated body portion, a bracing member connected with said lower bracket member adjacent said foot portion, a line carrying member extending transversely of said foot portion, and means for adjusting the position of said line carrying member longitudinally of said foot portion.

10. A clothesline bracket comprising an upper bracket member angular in cross section, means for pivotally mounting said upper bracket member on a support, a lower bracket member having an elongated body portion angular in cross section longitudinally adjustably mounted on said upper bracket member and having a foot portion angular in cross section extending laterally from said elongated body portion, a block longitudinally slidably mounted on said foot portion, a channel member carried by said block with the flanges thereof in embracing relation to said foot portion, a line carrying member mounted on said channel member and extending transversely of said foot portion and means for adjusting the position of said block longitudinally of said foot portion.

11. In a device for supporting clotheslines, a bracket member comprising an attaching portion and a foot portion extending perpendicularly to each other, said member being angular in cross section, a block longitudinally slidably mounted on one of said portions on one side thereof, a channel member on the other side thereof carried by said block, said channel member having flanges in embracing relation to said last mentioned portion, a line carrying member mounted on said channel member and extending transversely of said last mentioned portion and means for adjusting said block longitudinally of said last mentioned portion.

12. In a device for supporting clotheslines, a bracket member comprising an attaching portion and a foot portion extending perpendicularly to each other, said member being angular in cross

section, a block longitudinally slidably mounted on one of said portions on one side thereof, a channel member on the other side thereof carried by said block, said channel member having flanges in embracing relation to said last mentioned portion, a line carrying member mounted on said channel member and extending transversely of said last mentioned portion and means for adjusting said block longitudinally of said last mentioned portion, comprising a screw-threaded member mounted for rotation on but having means for holding said threaded member against movement axially of itself on said foot portion and being screw-threadedly connected with said block, said foot portion having a longitudinal slot therein and said block having a reduced portion thereon extending through said slot connected with said channel member.

13. In a device for supporting clotheslines, a bracket member comprising an attaching portion and a foot portion extending perpendicularly to each other, said member being angular in cross section, a block longitudinally slidably mounted on one of said portions on one side thereof, a line carrying member extending transversely of said last mentioned portion mounted on the other side thereof and connected with said block to move therewith, and means for adjusting said block longitudinally of said last mentioned portion.

14. In a device for supporting clotheslines, a bracket member comprising an attaching portion and a foot portion extending perpendicularly to each other, said member being angular in cross section, a block longitudinally slidably mounted on said foot portion on one side thereof, a line carrying member extending transversely of said foot portion mounted on the other side thereof and connected with said block to move therewith, means on said line carrying member engaging said foot portion to prevent twisting of said line carrying member on said foot portion and means for adjusting said block longitudinally of said foot portion.

FRANK SCHUDY.
